UNITED STATES PATENT OFFICE

2,562,404

INTERNAL-COMBUSTION ENGINE

Richard C. Aaland, Clermont, Fla., assignor to
Continental Motors Corporation, Muskegon,
Mich., a corporation of Virginia

Application May 9, 1947, Serial No. 747,026

6 Claims. (Cl. 123—90)

1

This invention relates to an internal combustion engine, and more particularly to the valving mechanism particularly applicable to an engine of the overhead valve type having a plurality of separate, aligned cylinder and cylinder head assemblies.

In internal combustion engines of the type aforesaid, considerable difficulty has been encountered in properly lining up the various apertures and bearings so as to support a single continuous camshaft operable with all said aligned cylinders.

An object of the present invention is to overcome the aforesaid difficulties in the manufacture and maintenance of overhead valve internal combustion engines of the general type as herein illustrated by providing a novel means for enclosing the camshaft portions spanning the space between the cylinder head structures.

A further object of the invention is to facilitate manufacture and maintenance of engines of the aforesaid type by providing an improved means for supporting the camshaft and cooperating valve actuating mechanisms and the drive therefor.

For a more detailed understanding of the invention, reference may be had to the accompanying drawings which illustrate one form which this invention may assume, and in which:

Fig. 1 is a fragmentary end view of a V-type internal combustion engine of the overhead valve type and more particularly of the type having a plurality of separate aligned cylinder and cylinder head assemblies.

Fig. 2 is a vertical fragmentary longitudinal sectional view of the engine taken on the line 2—2 of Fig. 1.

Fig. 3 is a fragmentary vertical transverse sectional view through the cylinder and cylinder head assembly, and showing the bearing structures for supporting said valve actuating mechanisms taken on the line 3—3 of Fig. 2, and

Fig. 4 is a further detail sectional view of the bearing structure, taken on the line 4—4 of Fig. 2.

The present invention is illustrated in the accompanying drawings in connection with a multi-cylinder V-type engine of the over-head valve type. It will be readily understood, however, that the principles of the invention may be embodied in other types of in-line multi-cylinder internal combustion engines. In the engine "A" herein illustrated, 10 designates the crankcase to which is secured a plurality of aligned engine cylinders 11, each having a cylinder head structure 12 secured thereto by conventional fastening means.

A crankshaft 15 is rotatably supported by the crankcase in suitable bearings, and a crankshaft gear 16 is drivingly connected to the crankshaft in any suitable manner. A compound layshaft 100

gear 17 meshes with the crankshaft gear and carries a beveled gear 18 meshing with another beveled gear 19, which drives the shaft 20, said shaft being preferably geared to the camshaft 21 by suitable gearing 22. Lubricating oil is fed to the hollow camshaft 21 from the oil duct 23, centrifugal force flowing said lubricating oil on the inner surface of the camshaft where same is fed longitudinally thereof and conducted as desired to various valve actuating mechanisms which are to be lubricated.

The camshaft 21 is supported at one end in a bearing 25 of the camshaft drive housing 26 which housing is secured at its lower end to the crankcase 10 and at its upper end to a cylinder head structure 12. The novel support for this camshaft, which extends longitudinally of the row of aligned cylinders, comprises a single bearing in each cylinder head structure, and where said camshaft extends between adjacent cylinder head structures, same is housed in an extensible and distortable housing 27 comprising a bellows 28 referred to in the trade as a "Sylphon," the flanges 29 of this housing being secured to the cylinder head structures.

This particular bellows type housing completely houses that portion of the camshaft bridging the gap between the cylinder heads, and because of its flexible character, any misalignment of the cylinder heads is taken care of by flexing of the bellows and this non-rigid connection does not induce any strains or stresses on the cylinder heads as might result from a rigid connection requiring a more or less perfect alignment of the side faces of the cylinder heads as well as the alignment of the bolt holes by which the intermediate housing is fastened to the cylinder heads.

The cylinder head structure carries a pair of rocker arm supports 30 and 31, to which are secured the bearing caps 30A and 31A. These bearing caps support the rocker arm shafts 32 which support the rocker arms 33, which are actuated by means of the cam portions 34 carried by the camshaft to operate the intake and exhaust valves 35. The camshaft portion in registration with the recess 36 in bearing cap 31A has a diameter closely fitting into the recess, while the camshaft portion in registration with the other bearing cap 30A is appreciably less in diameter as is likewise the diameter of the recess 37 in the bearing cap 30A. The recess 37 is machined on a diameter which is sufficiently large to have clearance with the camshaft, and is less than the machined diameter of the recess 36, so that the bearing cap cannot be assembled to the bearing support 31 when the camshaft is in place. Thus in assembly of the engine, either in initial assembly or reassembly after being serviced, the assembly of the bearing cap to its proper support is assured. Only bearing caps 31A carry oil ducts

40, which serve to conduct lubricating oil to the rocker arm shafts.

It will thus be observed that the camshaft is in reality supported in one bearing in each cylinder head, thereby particularly facilitating manufacturing and assembly of the camshaft in absolute alignment. Reassembly after servicing is accomplished with a minimum of error and with a minimum of time and labor by reason of this improved and novel construction.

It will be apparent to those skilled in the art to which this invention pertains, that various modifications and changes may be made therein without departing from the spirit of the invention or from the scope of the appended claims.

It is claimed:

1. In an internal combustion engine of the overhead valve type, a plurality of aligned cylinder structures, separate cylinder head structures secured to each cylinder structure, engine intake and exhaust valve actuating mechanism supported by said cylinder heads and including a single cam shaft for said plurality of cylinder and cylinder head assemblies, a single bearing structure carried by each of said cylinder head structures, and separate flexible camshaft housings secured to said cylinder head structures and enclosing the camshaft portions which bridge the gap between said cylinder head structures.

2. In an internal combustion engine of the overhead valve type, a plurality of aligned cylinder structures, separate cylinder head structures secured to each cylinder structure, engine intake and exhaust valve actuating mechanism supported by said cylinder heads and including a single cam shaft for said plurality of cylinder and cylinder head assemblies, a single bearing structure carried by each of said cylinder head structures, and separate flexible camshaft housings secured to said cylinder head structures and enclosing the camshaft portions which bridge the gap between said cylinder head structures, said flexible camshaft housings comprising an intermediate bellows portion permitting lateral flexing and axial distortion of said housings.

3. In a valve actuating mechanism for an internal combustion engine of the overhead valve type, a cylinder head structure for supporting said valve actuating mechanism, a camshaft extending transversely of the cylinder head structure and provided with cam means, rocker arms actuated by said cam means, and bearing means for supporting said rocker arms and comprising a pair of bearing bosses and cooperating bearing caps which are spaced longitudinally of the cam shaft, rocker arm shafts supported by said bearing caps, one only of said bearing boss and cap assemblies provided with bearing means for supporting the camshaft, said camshaft portion in registry with said other bearing boss and cap assembly having a reduced diameter and arranged to have clearance with respect to an aperture carried by said second boss and cap assembly, which aperture has a diameter less than the aperture of said first boss and cap assembly which supports the camshaft.

4. In a multi-cylinder internal combustion engine of the overhead valve type, a plurality of aligned cylinder structures, separate cylinder head structures secured to each cylinder structure, engine intake and exhaust valve actuating mechanism supported by said cylinder head structures and comprising a single cam shaft for said plurality of cylinder and cylinder head assemblies and provided with cam means, rocker

arms actuated by said cam means, and bearing means for supporting said rocker arms and comprising a pair of bearing bosses and cooperating bearing caps which are spaced longitudinally of the cam shaft, rocker arm shafts supported by said bearing caps, one only of said bearing boss and cap assemblies provided with bearing means for supporting the cam shaft, said cam shaft portion in registry with said other bearing boss and cap assembly having a reduced diameter and arranged to have clearance with respect to an aperture carried by said second boss and cap assembly, which aperture has a diameter less than the aperture of said first boss and cap assembly which supports the camshaft, the bearing boss and cap assembly in one cylinder head structure, and which is provided with bearing means being arranged adjacent to the bearing boss and cap assembly in the adjacent cylinder head structure which has an aperture constructed to have clearance with said cam shaft.

5. In a multi-cylinder internal combustion engine of the overhead valve type, a plurality of aligned cylinder structures, separate cylinder head structures secured to each cylinder structure, engine intake and exhaust valve actuating mechanism supported by said cylinder head structures and comprising a single cam shaft for said plurality of cylinder and cylinder head assemblies and provided with cam means, rocker arms actuated by said cam means, rocker arms actuated by said cam means, and bearing means for supporting said rocker arms and comprising a pair of bearing bosses and cooperating bearing caps which are spaced longitudinally of the cam shaft, rocker arm shafts supported by said bearing caps, one only of said bearing boss and cap assemblies provided with bearing means for supporting the cam shaft, said cam shaft portion in registry with said other bearing boss and cap assembly having a reduced diameter and arranged to have clearance with respect to an aperture carried by said second boss and cap assembly, which aperture has a diameter less than the aperture of said first boss and cap assembly which supports the cam shaft, the bearing boss and cap assembly in one cylinder head structure and which is provided with bearing means being arranged adjacent to the bearing boss and cap assembly in the adjacent cylinder head structure which has an aperture constructed to have clearance with said cam shaft, said cylinder head structures having openings through which said cam shaft extends, which openings have a dimension greater than the dimension of the cam shaft extending therethrough.

6. In a multi-cylinder internal combustion engine of the overhead valve type, a plurality of aligned cylinder structures, separate cylinder head structures secured to each cylinder structure, engine intake and exhaust valve actuating mechanism supported by said cylinder head structures and comprising a single cam shaft for said plurality of cylinder and cylinder head assemblies and provided with cam means, rocker arms actuated by said cam means, and bearing means for supporting said rocker arms and comprising a pair of bearing bosses and cooperating bearing caps which are spaced longitudinally of the cam shaft, rocker arm shafts supported by said bearing caps, one only of said bearing boss and cap assemblies provided with bearing means for supporting the cam shaft, said cam shaft portion in registry with said other bearing boss and cap assembly having a reduced diameter and ar-

ranged to have clearance with respect to an aperture carried by said second boss and cap assembly, which aperture has a diameter less than the aperture of said first boss and cap assembly which supports the cam shaft, the bearing boss and cap assembly in one cylinder head structure and which is provided with bearing means being arranged adjacent to the bearing boss and cap assembly in the adjacent cylinder head structure which has an aperture constructed to have clearance with said cam shaft, said cylinder head structures having openings through which said cam shaft extends, which openings have a dimension greater than the dimension of the cam shaft extending therethrough, and separate flexible cam shaft housings secured to said cylinder head openings and the cam shaft portions which

bridge the gap between said cylinder head structures.
